VALVE MECHANISM FOR INTERNAL COMBUSTION ENGINES

Arnold Edward Ludwig, Asbury Park, N. J.

Application February 26, 1941, Serial No. 380,610

6 Claims. (Cl. 123—81)

This invention relates to internal combustion engines, and is concerned primarily with the valves that control the intake and exhaust ports of the cylinders.

Under present-day conditions the valves which control the intake and exhaust ports of an internal combustion engine move into and out of a seated position in the valve opening, this being true whether the motor be of the V-type, L-head or overhead valve type of engine. Due to this fundamental characteristic of the operation of the valve, it has been necessary to employ various types of tappets and connections between the valve and the cam shaft which operates the same for the purpose of providing a fixed clearance.

Various attempts have also been made to make provision for automatically taking up wear in the valves. In all these cases now in use and available to the public, there is great danger of the valve sticking and serious damage resulting therefrom. Moreover, the need for the fixed clearances in the connections between the valve and the cam shaft to insure of proper seating of the valve often renders operation of the engine noisy to an annoying degree.

With the above-noted conditions in mind, this invention has in view as its foremost objective the provision in an internal combustion engine of novel valve mechanism for obviating the above-noted undesirable factors.

More in detail, this invention has an object the provision of valve mechanism designed to control the intake and exhaust ports of the cylinder of an internal combustion engine which is characterized as having an oscillating motion.

Still more in detail the invention has in view the provision of a valve member mounted for rotating oscillating movement and which is designed in one position to close the port with which it is associated, and in another position, establishes communication between said port and the cylinder.

In providing an oscillating valve of the type above-noted, a substantially cylindrical valve member is formed with a groove in the cylindrical face thereof. This valve member is mounted in a cap block that is in turn attached to the engine head so as to locate the valve adjacent to the port which it is intended to control.

When the cylindrical surface is disposed over the port, the latter is closed, but when the groove is brought opposite the port, communication between the port and the cylinder is established.

An important object of the invention is to pro-

vide effective seals between the valve member and the engine head when the valve is in port-closing position. This object is achieved by forming the valve member with notches defining shoulders that are adapted to engage complementary shoulders on the engine head. Thus, when a valve is moved into closed position, and a limited movement is reached, the shoulders of these notches engage to provide a good seal.

Yet another object of the invention is the provision of means for lubricating the valve member. The oscillation of the valve member in the cap block requires that it be properly lubricated. In accordance with this invention, the cap block is formed with recesses which receive a felt lubricating pad. These recesses open onto the top surface of the block and at the top surface are enlarged to provide a gutter which collects lubricant coming from the cam shaft and other instrumentalities of the motor.

A somewhat detailed feature of the invention is the provision of a cap block having an inclined top surface over which the lubricant is adapted to drain. As the lubricant drains across this inclined top surface, a portion thereof will be collected in the gutter to be fed to the felt lubricating pad. The latter engages the valve member to insure proper lubrication thereof.

Yet another object of the invention is the provision of novel and improved means for controlling the operation of the valve from the cam shaft. Whether a valve is associated with an exhaust or intake port, it is important that it remain in open or closed position for certain exactly determined periods during the cycle of operation.

This invention provides connections between an overhead cam shaft and the valve member for insuring of such accurately timed operation.

Yet another object of the invention is the provision of an internal combustion engine of the character above-noted including a valve member mounted in a cap block, together with means for adjusting the cap block with respect to the engine head on which it is mounted so as to provide for adjustment in the cap block commensurate with wear on the valve member.

Still another object of the invention is the provision of a valve member and cap block assembly of the character above-noted, together with oil sealing means which is interposed between the two. This oil sealing means is effective to prevent lubricating oil from running down into the combustion chamber of the cylinder.

Various other more detailed objects and ad-

vantages of the invention will in part become apparent and in part be hereinafter stated as the description of the invention proceeds.

The invention, therefore, comprises an oscillating valve for an internal combustion engine including novel characteristics as to its mounting, connections to the operating cam shaft, and lubrication.

For a full and more complete understanding of the invention, reference may be had to the following description and accompanying drawings wherein:

Figure 1 is a sectional view through the top portion of an internal combustion engine including valve mechanism, in accordance with the precepts of this invention.

Figure 2 is another sectional view similar to Figure 1, with parts omitted, developing the valve in a different position of operation.

Figure 3 is an enlarged detailed view in perspective of the valve member, certain cams on the cam shaft, and the operating connections therebetween.

Figure 4 is a perspective view of the cap block and associated parts in which the several elements are developed in exploded relation.

Figure 5 is an enlarged detailed sectional showing through the valve member and cap block, developing the manner in which the oil seal is mounted in the former.

Figure 6 is a detailed perspective view of an oil seal element per se, and

Figure 7 is a bottom plan of the cap block per se.

Referring now to the drawings, wherein like reference characters denote corresponding parts, and first more particularly to Figure 1, a block and head of an internal combustion engine are referred to in their entirety by the reference character E. The block itself is shown at 10 as formed with the usual cylinder opening 11 that is surrounded by the jacketed wall construction 12 which provides a circulatory cooling system. The head is shown at 13 as also being of a jacketed construction, and this head is formed with the opening 14 that is in alignment with and constitutes a continuation of the cylindrical opening 11. The head 13 carries a spark plug at 15 and is formed with a port 16 which, for the exemplary purposes of this specification, may be termed the intake port for the cylinder 11.

It is to be understood that the head 13 will be formed with both an intake and exhaust port for each cylinder of the engine. Whether the port be an intake port, or an exhaust port, in each instance it will be controlled by an oscillating valve of the type to be hereinafter described.

A cap block 17 is shown as mounted on the head 13. This cap block is shown in detail in Figure 4, and it will be noted that headed bolts 18 extend through openings 19 in the block to points of anchorage in the head 13 into which the lower ends of the bolts 18 are screwed. A plurality of shims 20 are interposed between the cap block 17 and the head 13, and by varying the number of these shims 20, adjustment between the block 17 and head 13 may be attained.

It will be noted from Figure 1 that the cap block 17 is also of a jacketed construction providing cooling chambers 21 which may be included as a part of the circulatory system of the engine by means of the openings shown at 22 which communicate with the water cooling jackets of the head 13. It is important to note that the shims 20 also function as sealing gaskets to

provide an effective seal between the cap 17 and head 13.

The under face of the cap-like block 17 is formed with an arcuate surface 23 and fitted in this recess 23 for oscillating movement therein is the valve member 24. The valve member 24 is substantially cylindrical in formation for the major part of its extent, but on the under side is cut away to form a groove designated 25.

It is notable that the head 13 is formed with an arcuate surface 26 that constitutes a substantial continuation of the arcuate surface 23 of the cap block 17. The head 13 includes another arcuate surface 27 adjacent the port 16.

Between the port 16 and arcuate surface 27 is a shoulder 28, while a somewhat similar shoulder is formed at 29 at the lower edge of the arcuate surface 26. The valve member 24 is notched at 30 to provide a shoulder complementary to the shoulder 28 and is formed with a projection at 31 that provides a shoulder that is complementary to the shoulder 29.

In the position of the valve depicted in Figure 1, the valve member 24 closes the port 16. Thus, the valve is intended to be in sealing position and to enhance the effectiveness of this seal, the shoulder 28 engages the complementary shoulder of the notch 30, while the shoulder 29 similarly engages the complementary notch of the shoulder 31. These shoulders and notches also constitute a limit of rotation of the valve in a clockwise direction (speaking with reference to the showing of Figure 1).

At substantially diametrically opposite points the valve member 24 is formed with a pair of elongated slots or grooves 32, each of which is intended to constitute a housing for an oil seal. The oil seal member is shown in detail in Figure 6 and designated 33. Expansion coil springs 34 are interposed between each member 33 and the bottom of the groove 32. Each of these oil seals 33 carries edge surfaces 35 that are intended to be urged into wiping engagement with the arcuate surface 23 of the cap block 17.

It will be noted that in the assembled position the cap block 17 has a top surface 36 that is inclined to the horizontal. Lubricant coming from the cam shaft which is disposed thereabove (to be later described) will fall on this top surface 36, and due to the inclination thereof, will drain thereover. At an appropriate point the surface 36 is formed with a gutter 37.

Slots 38 extend between the bottom of the gutter 37 and the arcuate surface 23, these slots being enlarged at the bottom to provide arcuate recesses 39. The slots 38, together with the recesses 39 and the cylindrical surface of the valve member 24, define a T-formation. Received in this formation is a lubricating member 40 which may be of any appropriate material, such as felt, whereby it is constituted a wick.

It will be noted that the wick 40 has a central web 41 formed with a notch 42 midway the extremities thereof, which accommodate the un-slotted bottom of the gutter 37. The legs of this web 41 project up into the gutter 37 and slightly above the surface 36, as shown in Figure 1. This felt 40 absorbs lubricant collected in the gutter 37 and transmits the same to the cylindrical surface of the valve member 24 to lubricate the latter.

The valve member 24 projects beyond the cap block 17 at one end and attached thereto is a fork member 43. Any appropriate means may be used to attach the member 43 to the valve

member 24, such as the screw fastening elements shown at 44. The fork member 43 carries a pair of legs 45 and 46, the upper portions of which are offset with respect to each other. A roller 47 is carried at the upper leg 45 while a second roller 48 is carried at the upper end of the leg 46, and these rollers 47 and 48 are in offset relation. An overhead cam shaft is designated 49 and it will be noted that this cam shaft is operatively connected with the drive shaft of the engine in any well-known manner. A cam 50 is drivably mounted on the shaft 49 and has a cam surface 51 that engages the roller 47. A second cam 52 is also drivably mounted on the cam shaft 49 and has a cam surface 53 in engagement with the roller 48.

To the end of enclosing the valve member 24 to as great an extent as practical, the groove defined by the arcuate surface 23 is closed at one end by an end wall 54. At the end carrying the fork 43 the cap block 17 is formed with a flange 55 that hangs over the forward face of the valve member 24, and serves to retain the latter in position.

While the operation of the above-described mechanism is believed to be obvious, it may be briefly outlined by noting that with the valve member 24 in position closing the port 16, the groove 25 is disposed at the top of the opening 14 in the head 13. An effective seal is provided by shoulders 28, 29, and notches 30, 31. The valve member 24 will remain in closed position just as long as it is required by the cycle of operation of the engine. As the cam shaft 49 rotates in a counterclockwise direction, (speaking with reference to the showing of the drawings), the cam surface 51 of the cam 50 forces the roller 47 to the left, thus rocking the valve into the open position depicted in Figure 2. In this position it will be noted that the groove 25 establishes communication between the port 16 and the cylinder 11. This open position is maintained just so long as the roller 47 is kept over to the left by the long end of the cam 50. As rotation of the cam shaft 49 continues, the cam surface 53 of the cam 52 engages the roller 48 to shift the latter to the right and bring the valve member 24 back into the closed position illustrated in Figure 1.

While a preferred specific embodiment of the invention is hereinbefore set forth, it is to be clearly understood that the invention is not to be limited to the exact construction illustrated and described, because various modifications of these details may be provided in putting the invention into practice, within the purview of the appended claims.

I claim:

1. In an internal combustion engine including an engine block and head formed with a cylinder opening, there being a port in said head communicating with said opening, valve mechanism for said port comprising a cap block anchored to said head and forming an arcuate recess above said cylinder opening, a substantially cylindrically shaped valve member mounted for oscillation in said recess, means carried by said valve member for establishing communication between said port and said cylinder opening when said means is brought into registry with said port, means for oscillating said valve member, and sealing means between said valve member and said head which is rendered effective when said valve member closes said port, said means including a shoulder

extending outwardly from the periphery of said valve and arranged to span the joint between said valve and the wall of said arcuate recess.

2. In an internal combustion engine including an engine block and a head formed with a cylinder opening, there being a port in said head communicating with said cylinder opening, and an overhead cam shaft, valve mechanism below said cam shaft for said port comprising a valve member formed with a recess that is adapted to be brought into registry with said port to establish communication between said port and said cylinder opening, an arm carried by said valve member, cam means on said cam shaft engaging said arm to oscillate said valve member, said cam shaft and valve being arranged for lubrication in succession by a common source.

3. In an internal combustion engine including an engine block and a head formed with a cylinder opening, there being a port in said head communicating with said cylinder opening, and an overhead cam shaft, valve mechanism below said cam shaft for said port comprising a valve member, an arm carried by said valve member and formed with spaced cam engaging means, cams on said cam shaft engaging said spaced cam engaging means, and means for collecting oil from said cam shaft to supply lubricant to said valve member.

4. In an internal combustion engine including an engine block and a head formed with a cylinder opening, there being a port in said head communicating with said cylinder opening, and an overhead cam shaft, valve mechanism below said cam shaft for said port comprising a cap block carried by said head and formed with a recess above said cylinder opening, a substantially cylindrically shaped valve member in said recess and formed with a groove adapted to be brought into registry with said port, an arm carried by said valve member, cam means on said cam shaft engaging said arm to oscillate said valve member, and means for catching a limited quantity of oil from said cam shaft and introducing it by gravity between said cap block and said valve member.

5. In an internal combustion engine including an engine block and head formed with a cylinder opening, there being a port in the head communicating with the said cylinder opening, valve mechanism for said port comprising a cap block anchored to said head and formed with an arcuate recess above said cylinder opening, said cap block having an inclined upper surface formed with a gutter, the cap block also being formed with slots extending between said gutter and said arcuate recess, a wick member in said slots projecting into said gutter, a valve member in said recess formed with a groove adapted to be brought into registry with said port, and means for oscillating said valve member.

6. In an internal combustion engine having a cylinder and a port communicating therewith, valve mechanism for said port comprising a cap block carried by said engine and formed with a recess, a valve member mounted for oscillation in said recess and formed with a groove adapted to be brought into registry with said port to establish communication between said port and said cylinder, a shoulder extending from the periphery of said valve member adjacent one edge of said groove and adapted to span the joint between said valve member and said recess and means for oscillating said valve member.

ARNOLD EDWARD LUDWIG.
